UNITED STATES PATENT OFFICE.

HARRY E. SCHOENHUT, OF PHILADELPHIA, PENNSYLVANIA, ASSIGNOR TO PAT SULLIVAN, OF NEW YORK, N. Y.

DESIGN FOR AN ANIMAL DOLL.

Application filed March 21, 1924. Serial No. 9,019. Term of patent 14 years.

To all whom it may concern:

Be it known that I, HARRY E. SCHOENHUT, a citizen of the United States, residing at E. Hagut and Sepowa Streets, in the city of Philadelphia, county of Philadelphia, and State of Pennsylvania, have invented a new, original, and ornamental Design for an Animal Doll, of which the following is a specification, reference being had to the accompanying drawing, forming a part hereof.

The figure of the drawing is a perspective view of an animal doll showing my new design.

I claim:

The ornamental design for an animal doll substantially as shown.

HARRY E. SCHOENHUT.
